US0D1062464S

(12) **United States Design Patent** (10) **Patent No.:** **US D1,062,464 S**
(45) **Date of Patent:** **** Feb. 18, 2025**

(54) **CONTAINER**

(71) Applicant: **Colgate-Palmolive Company**, New York, NY (US)

(72) Inventors: **Scott Beckerman**, South Orange, NJ (US); **Renee Marie Riethmiller**, Larchmont, NY (US)

(73) Assignee: **Colgate-Palmolive Company**, New York, NY (US)

(**) Term: **15 Years**

(21) Appl. No.: **29/873,730**

(22) Filed: **Apr. 6, 2023**

Related U.S. Application Data

(62) Division of application No. 29/773,169, filed on Mar. 8, 2021, now Pat. No. Des. 985,394.

(57) **CLAIM**

The ornamental design for a container, as shown and described.

DESCRIPTION

FIG. 1 is a front perspective view of a container according to the new design;

FIG. 2 is a front view thereof;

FIG. 3 is a rear view thereof;

FIG. 4 is a right side view thereof;

FIG. 5 is a left side view thereof;

FIG. 6 is a bottom view thereof; and,

FIG. 7 is a top view thereof.

The broken lines formed by linear segments of equal length illustrate portions of the container that form no part of the claimed design.
